UNITED STATES PATENT OFFICE.

BENJAMIN J. LESLIE, OF BUTLER, KY., ASSIGNOR, BY MESNE ASSIGNMENTS,
OF ONE-HALF TO SAMUEL E. HUDDLESTUN, OF SAME PLACE.

SHOVEL-PLOW.

SPECIFICATION forming part of Letters Patent No. 320,074, dated June 16, 1885.

Application filed June 2, 1884. (No model.)

To all whom it may concern:

Be it known that I, BENJAMIN J. LESLIE, a citizen of the United States, residing at Butler, Pendleton county, Kentucky, have 5 invented new and useful Improvements in Shovel-Plows, of which the following is a specification.

My invention relates to shovel-plows; and it consists of an improved construction of the sheth or standard and its connection with the draft-bar, handles, and shovel or plowshare, its object being to form a light, durable, strong and economic construction of these parts. For this purpose I use for the sheth a casting 15 with a flattened head, suitably formed for attachment to the under side of the draft-bar and pierced with a slot for the passage of the colter. The foot of the casting is shaped for the attachment of the handles on either side 20 of a central rib, and for the attachment of the share or shovel, as hereinafter more fully described.

Referring to the drawings, where similar letters refer to similar parts, Figure 1 represents a perspective view of a shovel-plow 25 complete of my improved construction; Fig. 2, a detached view on a larger scale of the sheth, showing the connection of the handles thereto, with part of the shovel removed to 30 show the attachment of the latter to the sheth. Fig. 3 is a section taken on a plane, *a b*, (in Fig. 2,) showing in further detail the manner of connecting handles to sheth, and Fig. 4 is a detached view of part of draft-bar, showing 35 a modified form of the connection of sheth thereto when the plow is designed to be used in hard ground, or as a two-horse plow, as hereinafter more fully described.

The draft-bar *A*, clevis *B*, colter *C*, handles 40 *D D*, and shovel *E* are of the usual construction, and require no detailed description.

I use for the sheth *F* a casting with lateral strengthening-rib *f*, thicker in line of draft than in the direction at right angles thereto, 45 and having a flattened upper part, *V*, pierced with a rectangular slot to admit the head of the colter *C*, and with holes for the passage of bolts *d d'*. The lower part is constructed with the recessed sides divided by a central 50 rib, *g*. In the former lie the two handles *D D*, clamped against the dividing-rib *g* by a bolt,

e, and further held in place by the piece *m*, forming the bottom of the recessed spaces. The extension-piece *H*, to which the shovel 55 *E* is secured, is pierced with a rectangular slot, *h*, widest next the blade of the shovel, and in fastening the shovel to it I first provide a wedge of wood grooved next the bolt *i* to allow its free passage and of such size that when the bolt *i*, which is permanently attached to the 60 blade of the shovel, is inserted into the slot *h* and the nut screwed home it will completely fill the hole, wedging the bolt firmly against the side *s* of the wedge-shaped hole, as shown in Fig. 2, the object being to form a firm connection which shall not be absolutely rigid 65 and unyielding, but shall have sufficient elasticity to receive without injury shocks and sudden strains to which this part of a plow is peculiarly liable from striking stones or 70 roots in plowing.

In order to hold more securely the shovel-blade or plowshare *E* in position, I may provide a set-screw, (not shown in the drawings,) threaded in the end of shoulder or extension-piece *H*, immediately under the shovel-blade *E*, which upon being screwed in the proper direction forces the wedge-block filling the slot *h* more firmly against the bolt *i*, which holds the shovel-blade in its place on the extension piece or shoulder *H*. 75

For use in hard ground, or when I desire to use two horses attached to the plow, I may modify the attachment of sheth to draft-bar (shown in Fig. 2) to the form indicated in 85 Fig. 4, in which, instead of using two screw-bolts, *d d'*, (shown in Figs. 1 and 2,) I form an angle-block, *t*, on the top plate, pierced with slot for the passage of the wedge-pin *c* and grooved to allow the yoke *d'* to pass over its 90 upper surface. I further provide the flattened portion of the sheth *V* with lugs *k*, to form abutting plates, through which pass the threaded ends of the yoke *d'*. Upon supplying the nuts and screwing them home the 95 sheth and the top plate are firmly fastened to the draft-bar. In addition, I use the bolt *d*, as previously shown, and further provide the rib or tenon piece *r*, to be mortised into the under surface of the draft-bar, preventing any 100 lateral motion.

The advantage of this form of connection

will be appreciated by any one familiar with this kind of plow. The colter C being inserted through the upper part of the sheth, and fitting tightly in a suitable slot therein, 5 and passing likewise through the plate on top of the draft-bar, wedged tightly therein by the wedge-pin c, is thus made a part of the combination of cast sheth, yoke d', and top plate, and any pressure on the colter from 10 striking roots or stones in plowing only serves to hold the parts more firmly together, since it tends to push the upper plate forward, increase the strain in the yoke d', and consequently clamp the sheth more firmly against 15 the draft-bar.

I claim and desire to secure by Letters Patent—

1. A shovel plow with a cast sheth having a flattened head suitable for attachment to 20 under side of draft-bar, and having a rectangular slot therein for the passage of the colter, in combination with the handles D D, at-

tached to the foot of sheth, lying within recesses in the latter, and the shovel-blade E, secured to a shoulder or extension-piece H, at 25 the foot of the sheth, substantially as described.

2. In a shovel-plow, the combination, with a cast sheth carrying the shovel-blade and handles attached thereto, as described, and having a flattened head adapted to receive the 30 ends of a stirrup bolt or yoke, d, and with rib or tenon piece r, of an upper plate having an angle-block, t, formed thereon, adapted for the passage of colter C and insertion of wedge-pin c, and further adapted to receive 35 the curved loop of the yoke d', and the yoke d', substantially as described.

In testimony whereof I have hereunto set my hand in the presence of two subscribing witnesses.

BENJAMIN J. LESLIE.
